US0D1011671S

(12) **United States Design Patent** (10) Patent No.: **US D1,011,671 S**
(45) Date of Patent: ** Jan. 16, 2024

(54) **CONTAINER**

(71) Applicant: **BWAY CORPORATION**, Atlanta, GA (US)

(72) Inventors: **Frano Luburic**, Costa Mesa, CA (US); **John Homan**, Naperville, IL (US)

(73) Assignee: **BWay Corporation**, Atlanta, GA (US)

(**) Term: **15 Years**

(21) Appl. No.: **29/789,609**

(22) Filed: **Oct. 4, 2021**

(56)

(57) **CLAIM**

The ornamental design for the container, as shown and described.

DESCRIPTION

FIG. 1 is a perspective view of a container; FIG. 2 is a perspective view of a container; FIG. 3 is a top view of a container; FIG. 4 is a bottom view of a container; FIG. 5 is a front view of a container; FIG. 6 is a side view of a container; and, FIG. 7 is an enlarged partial cross-sectional view of a container taken from line 7-7 in FIG. 3. The broken lines shown in the drawings illustrate portions of the container and form no part of the claimed design.

1 Claim, 7 Drawing Sheets

See application file for complete search history.
